GARMENT CONSTRUCTION

Herbert Roy, New York, N. Y.

Application May 12, 1942, Serial No. 442,705

4 Claims. (Cl. 2—93)

This invention relates generally to wearing apparel, and more particularly to garments having special back constructions.

Among the objects of this invention lies the provision of novel garment back structure permitting a greater amount of freedom of movement by the wearer and an enhancement of the appearance and style of the garment.

Another object herein lies in the provision of novel garment back construction, having the above described characteristics, which is readily incorporated in garments of known general construction, and requiring a minimum of change in fabricating technique or the basic garment styling.

Another object herein lies in the provision of a novel garment back structure which operates with a maximum of comfort to the wearer, in which means are provided for constantly maintaining the back of the garment in a condition to present a neat and trim appearance.

A still further object herein lies in the provision of a novel expansive back construction, maintaining a substantially uniform efficiency throughout the life of the garment, and which requires no replaceable parts.

Garments constructed in accordance with the present invention require an extremely small amount of additional material so that the same, by reason of altered cutting, may not require material in an amount greater than an amount normally used for constructing a garment when the present invention is not utilized.

A further feature herein lies in the fact that garments made in accordance with the present invention require an extremely small amount of additional labor over that normally required.

As contrasted with prior constructions for attempting to produce similar effects, the present invention is more efficient and cheaper to install, with the result that the same may have a consequent wide scale distribution, sale, and use.

While the expansive back constructions in the present invention are extremely efficient in use, it may be noted that the same do not add appreciably to the bulk of the garment. Thus garments made in accordance herewith of light-weight materials, when worn in warm weather, are substantially as cool as others heretofore known.

The use of inwardly directed pleats in the backs of garments, said pleats being disposed adjacent the connection of the upper rear portions of the sleeve to the garments backs, is well

known and such construction has been applied to various types of uniforms and to sports clothing. A difficulty encountered with this construction, however, lies in the fact that if the additional reservoir of material included within the inwardly directed pleat is of low order, insufficient freedom of movement is permitted the wearer as he brings his arms forward. In an effort to compensate for the relatively large amount of additional material needed in order to provide sufficient freedom, the depth of the pleats has been increased. This has brought about another difficulty in that after the pleat has been opened by a wearer's arm movement, the cloth passes a "dead center" position, snaps outwardly of itself, and presents an undesirable pucker or outward bulge. While elastic means have been heretofore utilized to interconnect the inner bights or folds of the pleats, these have been subject to serious objections. Where individual elastic straps have been used, they have caused an uneven outward appearance in the back of the garment. Where the elastic interconnection has been of a relatively large size, the bulk and comfort of the garment has been affected. Furthermore, all constructions using elastic mediums have been subject to the disadvantage that the elastic medium did not give a substantially uniform performance over a period of time and the elastic medium was usually subject to the deleterious effects caused by cleaning solvents.

In accordance with my improved construction, advantage is taken of the effects of gravity, the natural resiliency of the fabric of which the garment is composed, and of an unusual formation and interconnection of the garment parts, as will be more fully set forth hereinafter.

The above recited objects and other incidental ends and advantages will more fully appear in the progress of this disclosure and be pointed out in the appended claims.

In the drawings, forming a material part hereof, similar reference characters designate corresponding parts throughout the several views, in which:

Fig. 1 is a view in perspective, as seen generally from the rear, of a garment as worn, embodying the invention, with the externally visible parts shown in a normal or unstressed condition thereof.

Fig. 2 is a fragmentary view in perspective taken similarly to Fig. 1, but showing the parts associated with the left shoulder in a position taken thereby when under stress.

Fig. 3 is a fragmentary rear elevational view

of the garment back shown in Fig. 1 with adjacent parts removed for purposes of clarity.

Fig. 4 is a front elevational view of Fig. 3.

Fig. 5 is a schematic enlarged horizontal sectional view, as might be seen from the plane 5-5 on Fig. 4, the thickness of some of the parts being exaggerated.

Fig. 6 is a schematic enlarged horizontal sectional view as might be seen from the plane 6-6 on Fig. 5, the thickness of some of the parts being exaggerated.

Fig. 7 is a schematic enlarged vertical sectional view as might be seen from the plane 7-7 on Fig. 4, the thickness of some of the parts being exaggerated.

Fig. 8 is a front elevational view of the front pleat elements and the interconnecting element, shown as removed from the other parts on Fig. 4.

Fig. 9 is a schematic enlarged vertical sectional view of a second embodiment, as might be seen from the plane 7-7 on Fig. 4, the thickness of some of the parts being exaggerated.

Fig. 10 is a schematic enlarged horizontal sectional view of a third embodiment as might be seen from the plane 6-6 on Fig. 4, the thickness of some of the parts being exaggerated.

Turning now to the first embodiment of the invention, illustrated in Figs. 1 to 8, inclusive, it will be seen (Figs. 1 and 3) that the garment generally indicated by numeral 10, as worn may present externally the usual appearance of a coat in which provision has been made in the back 11 for pleats 12 and 13 which provide a reservoir of additional material which comes into use when the sleeves 14 or 15 are brought forwardly in a position to increase the distance between the rear lines of anchorage 16 and 17. The lines of anchorage are the lines along which interconnection takes place between the upper rear portions 18 and 19 of the sleeves 14 and 15 and the front pleat elements 20 and 21.

The rear lines of anchorage at the lower portions thereof, that is to say, below the lowermost point of connection between the upper portions 18 and 19 of the sleeves, and extending downwardly to the waistline 22 (for example, line 23 on Fig. 2) are connected to the front quarters 24 and 25 of the garment. The construction of the garment 10 below the waistline 22 includes the lower front quarter portions 26 and 27 and lower rear quarter portions 28 and 29. The lower rear quarter portions 28 and 29 may be disconnected along the vent 30 in the usual manner.

The pleats 12 and 13 are preferably substantially V-shaped in horizontal section (see Figs. 5 and 6) and they include the front pleat elements 20 and 21 and the rear pleat elements 30 and 31. The rear pleat elements are preferably formed by oppositely and inwardly folding toward each other the free vertical edges 32 and 33 of the upper rear quarters 34 and 35. The remaining inner vertical edges 36 and 37 are folded upon themselves and the bights 38 and 39 are interconnected by the central back seam 40. Thus, the folds 41 and 42 form the optical outer margins of the back 11. The folds 41 and 42 are preferably secured permanently in place by means of rows of stitching 43 and 44. The rear pleat elements 30 and 31 extend continuously from the shoulder seam lines 45 and 46 to the waistline 22 and in actual construction preferably extend downwardly so that the lowermost edges 47 and 48 thereof are substantially co-extensive with the lowermost edges 49 and 50 of the front pleat elements 20 and 21.

As best seen in Figs. 4 and 8 of the accompanying drawings, the front pleat elements 20 and 21 are of substantially the same vertical length as the rear pleat elements 30 and 31, respectively, and they extend from the shoulder seam lines 45 and 46 to the waistline 22, and extend sufficiently therebelow so that the lower edges thereof 49 and 50 are preferably substantially co-extensive with the lowermost edges of the rear pleat elements, as has been set forth above. The outer vertical edges 51 and 52 preferably extend laterally outwardly of the folds 41 and 42, as best seen in Fig. 3, and these edges 51 and 52 are seamed to the upper rear sleeve portions 18 and 19 and the rear edges of the front quarter portions 24 and 25 along the lines of anchorage 16 and 17. The inner opposed edges 53 and 54 of the front pleat elements are of peculiar configuration as best seen in Fig. 8 and include the upper rectilinear portions 55 and 56, the vertical curved portions 57 and 58, and the horizontal curved portions 59 and 60. The vertical and horizontal curved portions 57-60 define the upper limits of the interconnecting element 61, which may be formed by inwardly extending integral extensions of the front pleat elements and designated as interconnecting members 62 and 63. The lower edges of the interconnecting members 64 and 65 are preferably co-extensive with the edges 49 and 50. The inner opposed vertical edges 66 and 67 of the interconnecting members 62 and 63, respectively, are folded forwardly and outwardly about themselves to form the bights 68 and 69, and are interconnected by any suitable means 70, such as a row of stitches. The inner edges 32 and 33 of the rear pleat portions 30 and 31 are connected by rectilinear lines of stitching 73 and 74 to the upper rectilinear portions 55 and 56 of the inner opposed edges 53 and 54 of the front pleats 20 and 21, respectively; while the vertical curved portions 57 and 58 and the horizontal curved portions 59 and 60 are reinforced by a curvilinear line of stitching 75. The lowermost portions of the front pleat elements 20 and 21 and the interconnecting members 62 and 63 are operatively connected to the lower portions of the back 11 by a row of stitches 71 at the waistline 22, as best seen in Fig. 7. This row of stitches 71 may, where desired, be doubled for greater strength and improved appearance.

The rear collar line 72 is seen in Figs. 3 and 4 and may have any suitably constructed collar associated therewith in a manner well known in the art. Assuming the rear collar or neck line 72 to be located in a usual position, and the waistline 22 to be located in a position corresponding to the waistline of the wearer, it may be noted that the horizontal curved portions 59 and 60 of the edges 53 and 54 are disposed within the lowermost fifth of the total distance between the waistline 22 and the neckline 72. This positioning of the horizontal curved portions 59 and 60 may be varied within certain limits. I have found that the positioning shown is most suitable and effective for the average figure. If the upper edges, that is to say, the horizontal curved portions 59 and 60 of the interconnecting element 61, are raised considerably, a limit will be reached when, for all practical purposes, all increase in distance between the lines of anchorage 16 and 17 will be prevented and the purpose of the garment construction will be defeated. This is so because the interconnecting element 61 as well as the front pleat portions 20 and 21, and the rear pleat portions 30 and 31, are preferably com-

posed of the same material as the balance of the garment. Thus, while this fabric may be woven of wool having a relatively high twist and therefore be possessed of some resiliency, as contrasted with prior art constructions in which a material containing rubber or latex threads such as "Lastex" are used, the interconnecting element 61 and the front pleat elements 20 and 21 may be properly described as being inelastic.

If the horizontal curved portions 59 and 60, forming the upper edge of the interconnecting element 61, are lowered toward the waistline 22, a limit will be reached when, for all practical purposes, the pleat seating or returning action of the interconnecting element 61 will be lost.

When the back 11 and all of the connected structure, as previously described as being integrated therewith, is operatively associated with the balance of the garment in a manner well known in the art, as presently understood the operation of the invention is as follows:

For example, if the left sleeve 14 is elevated forwardly to a position shown in Fig. 2, by reason of the action of the wearer's arm the pleat 12 will open up, and previously concealed portions of the front pleat element 20 and the rear pleat element 30 will be pulled out into view, and where the movement of the sleeve 14 is considerable, said pleat elements will pucker outwardly therefrom, forming a bulge of material. This outward movement of the front and rear pleat elements 20 and 30 will cause a corresponding outward movement of the upper rectilinear portion 56. If a corresponding arm movement takes place within the sleeve 15, there will be a similar but opposite movement of the portion 55. These movements are illustrated diagrammatically by dot-dash lines in Fig. 4. The portions 57 to 60, inclusive, form a catenary 76 and outward movement of the portions 55 and 56 will cause a straightening of the curve of the catenary, and hence its elevation. Since the lowermost portions of the interconnecting element 61 are connected to the waistline of the garment by the row of stitches 71, this will cause a corresponding distortion and elevation of the lower rear quarters 28 and 29, which distortion will be transmitted to other connected parts, such as the forward lower quarters 26 and 27 and the upper rear quarters 34 and 35. When the stress upon the lines of anchorage 16 and 17 outwardly of the garment is removed by reason of the return of the sleeves to the normal, relaxed position thereof, the rear quarters 28, 29, 34 and 35, in lowering to the normal position thereof, exert a downward pull upon the catenary 76, which in turn causes a straightening out of the portions 55 and 56, which pull the inner apices adjacent the line of stitching 73 and 74 into their normally retracted and concealed positions.

When the catenary 76, as has just been described above, is straightened, it is believed there is also some tendency for the formation of undulations in the interconnecting element 61. The formation of these undulations takes place against the pressure of the small parts of the wearer's back thereagainst, and hence it is believed that this pressure, too, facilitates the return of the catenary 76 to its normal lower position after the stress upon the sleeves has been removed. It is also believed that during a period of stress, distortion takes place within the front pleat elements 20 and 21 and in the interconnecting members 62 and 63. This distortion results

in a temporary change in external peripheral configuration of these parts and in a corresponding expansion or compression of certain areas in the fabric of which they are composed, disturbing the normal equilibrium thereof. In returning to a balanced condition, these fabric portions tend to pull the pleats 12 and 13 into their normally seated position and arrangement.

Turning now to the second embodiment of the invention, illustrated in Fig. 9, for the purpose of avoiding needless repetition, parts corresponding to those of the first embodiment are given the same reference characters with a single prime suffix. This form of the invention differs from the first embodiment in that the operative connection between the lower edges of the interconnecting element 61' and the waistline 22' of the back 11' is omitted. In this construction the elevation of the interconnecting element 61' is therefore not as directly transmitted to the parts connectively associated with the waistline of the garment and the gravity effect is not as great. Distortion of the front pleat elements and the interconnecting members does take place, however, and the pleat seating action, after shoulder and arm stress is removed, is obtained.

In the third embodiment of the invention, illustrated in Fig. 10, again repetition is avoided by using reference characters corresponding to the first embodiment with an addition of a double prime suffix.

The third embodiment differs from the first embodiment in that the inner edges 68'' and 69'' are not only interconnected with each other, but are also connected to the central back seam which, in turn, connects the inner opposed edges of the rear quarters 34'' and 35''. The single row of stitches 40'' thus performs not only its own function but also performs the function of the means 70. In this construction the movement of the interconnecting element 61'' is more directly transmitted to the adjacent garment parts and more particularly to the upper rear quarters 34'' and 35'' of the back 11''.

It may thus be seen that I have disclosed a novel and useful garment back construction which constitutes an improvement over the heretofore known constructions for use of inverted pleats or similar cloth reservoirs for promoting arm movement freedom. My construction is consistent in operation and operates effectively throughout the life of the garment, being subject to no deleterious action by the use of cleaning solvents. Only relatively small additions of material are required, which, by adjustment in cutting, may actually result in no increase in the total yardage required by a given garment.

This construction is primarily directed to comfort and appearance and is therefore especially suited for use in connection with uniforms of our armed services, facilitating the movement of the soldier or officer as he goes through his duties and preserving, at all times, a neat appearance in the garment.

I wish it to be understood that I do not desire to be limited to the exact details of construction shown and described, for obvious modifications will occur to a person skilled in the art.

70 I claim:

1. A garment comprising: sleeves; a garment back having a plurality of pleats on the inner surface thereof, and an interconnecting control element joining said pleats, said interconnecting control element being substantially inelastic and

disposed below the level of the points of connection of the sleeves to the back of the garment.

2. A garment as claimed in claim 1, in which the interconnecting control element is composed of material having substantially the same degree of resiliency as the material of which the pleats are composed.

3. A garment comprising: sleeves; a garment back composed of material, the width of the material being greater than the normally required width of the back, the excess of said material being folded into a pair of oppositely disposed pleats, and an interconnecting control

element joining said pleats, said interconnecting control element being disposed substantially below the lowest point of connection of the sleeves and said pleats.

5 4. A garment comprising: sleeves; a garment back having a pair of inwardly and oppositely disposed pleats on the inner surface of said back, and an interconnecting control element joining said pleats, said interconnecting control element having the upper edge thereof disposed below the lowest points of connection between said sleeves and said back.

HERBERT ROY.
